FILAMENT STRUCTURE FOR ELECTRON
DISCHARGE DEVICEWilliam N. Parker, Lancaster, Pa., assignor to
Radio Corporation of America, a corporation
of Delaware

Application May 26, 1949, Serial No. 95,432

13 Claims. (Cl. 313—273)

1

The present invention relates to electron discharge device electrode structures and more particularly to electrodes provided with mounting heads, and a method of making the same, suitable for quick detachable interlocking engagement with the support members thereof particularly useful in electron discharge devices.

It is well known that a series limitation of electrode structures results from deformation thereof during processing or operation. In the main, such deformations results from thermal expansion of the electrode and mount, and constructions utilized heretofore have only been partially successful in overcoming this with the result that devices have electrode structures therein, in particular electron discharge devices, have been seriously limited in merit. The problem presented by such deformation is aggravated as the size of the affected parts is increased, nevertheless, even in the smallest tubes it must be effectively dealt with if the maximum merit is to be obtained.

One of the specific causes of such deformation has been the manner in which electrodes heretofore have been connected to their support members. In the co-pending application of Lloyd P. Garner filed May 26, 1949, Serial Number 95,398, (now U. S. Patent No. 2,548,184), assigned to the same assignee as the present application, there is disclosed a novel hook or clip-in type quick detachable interlocking connection between an electrode and its support members which substantially minimizes the bending forces applied to the electrode at the point or points of contact with its support members as the various parts expand and contract.

I have found that such bending forces and consequent deformation of the electrode can be further reduced and substantially eliminated and the electrode maintained accurately and precisely positioned in accordance with my invention.

It is therefore a principal object of my invention to provide an electron discharge device having an improved electrode structure, the elements of which may expand and contract without causing deformation of the electrode elements.

Another object of my invention is to provide an electrode mounting head having knife-edges by which the electrode may be interlocked in a quick detachable manner with its supports and which permits the electrode to rock freely about its supports without binding.

Still another object of my invention is the provision of an electrode having a mounting head

2

for quick detachable connection to the support therefor which automatically centers the electrode and maintains the same precisely located.

Yet another object is the provision of a method for manufacturing an electrode with a mounting head having accurately formed knife-edges which eliminates tedious and difficult machining operations and in accordance with which the knife-edges are formed by hot-heading or punching.

10 In carrying my invention into effect, I preferably provide the mounting head of an electrode with a knife-edge bearing surface extending in a plane which intersects the axis of the electrode.

The novel features that are considered characteristic of this invention are set forth with particularity in the appended claims. The invention as well as additional objects and advantages thereof will be best understood from the following description when read in connection with 15 the accompanying drawings, in which

Figure 1 is an elevational view partly in section of an electron discharge device embodying my invention;

Figure 2 is a fragmentary perspective view on 20 an enlarged scale of an electrode mounting head constructed in accordance with my invention;

Figure 3 is a front elevational view thereof partially in section;

Figures 4 and 5 are front elevational views 25 partially in section of modifications thereof also constructed in accordance with my invention;

Figure 6 is a plan view of the electrode shown in Figure 2 mounted in an annular support; and

Figure 7 is a schematic view illustrating the 30 operation of my invention.

Referring now to the drawings wherein like reference characters denote corresponding parts to Figures 2 and 3 in particular, an electrode 10 has a mounting head 11 provided with knife-edges 12 which seats in a V groove 13 formed in mounting block or support 14 and at right angles to a slot 15 also formed therein. Knife-edges 12 contact mounting block or support 14 35 along line A—A which preferably intersects axis B—B and at right angles thereto. To permit the desired unimpeded rocking of electrode 10 about line A—A V groove 13 has a greater angle than the intersecting planes forming knife-edges 12. I have found a knife-edge angle of 60 degrees 40 and a V groove angle of 90 degrees satisfactory although other appropriate combinations may be used.

As will be more fully pointed out hereinbelow, 45 I form knife-edges 12 leaving residual radius or

fillet 16. Furthermore, though slot 15 is large enough to give free clearance to electrode 10 as it rocks about line A—A, it is narrow enough so as to co-act with residual radius 16 on the sides of the electrode and thereby center the electrode in the slot. This prevents the electrode from moving about in the V groove and slot as the mounting block or support executes a succession of movements.

As shown in Figure 4, an electrode 17 has a mounting head 18 formed with relatively large residual radii or fillets 19 while in Figure 5 electrode 20 is provided with knife-edges 21 which are not co-linear but are swept up. In both instances contact is made in two points 22, 23 respectively, and forming a straight line intersecting the axis of the electrode; thereby avoiding having undesirable bending moments acting on the end of the electrode.

As noted hereinabove my invention is particularly useful in electron discharge devices but may also be advantageously used in electric heating furnaces or other devices. Referring to Figure 1 electron discharge device 24 is a high power tube capable of a power output of the order of 500,000 watts and forms the subject matter of my co-pending joint application with Lloyd P. Garner and Willis E. Harbaugh, filed March 17, 1949, Serial Number 81,932 (now U. S. Patent No. 2,544,664), and which is assigned to the same assignee as my present application.

Electron discharge device 24 is an internally water cooled triode having a cathode and grid, each of which comprises a circular array of axially tensioned discrete elements or bar-like sections indicated respectively at 25 and 26, surrounded by a cylindric anode 27 and all are housed in a demountable evacuated envelope as shown.

Each of the cathode elements or sections 25 is supported adjacent its upper ends by a laminated flexible support means indicated generally at 28 supported from central conducting tubular support member 29 which is connected to a copper diaphragm 38 by means of which it is connected electrically to terminal ring 30.

Still with reference to Figure 1, it is seen that the other or lower end of each cathode element or section 25 is inflexibly mounted in ring 31 brazed to outer cathode conducting support 32 at the lower end of a beam former array. Conducting support member 32 is coaxial and concentric with conducting support 29 and has a lower portion of increased diameter which, below terminal ring 33, forms part of the exterior envelope of the tube. The upper portion of conducting support 32 which is in the active region of the device 24 has a plurality of grooves machined therein, one for each of the cathode sections of which there are forty-eight in the tube illustrated. Said grooves are separated by lands 34 which function as the beam former array and focus the electron stream emitted from each cathode section. It is apparent, therefore, that each cathode is flexibly mounted at one end to one conducting support member and inflexibly mounted at the other end to the other conducting support member. Further it should be noted that the conducting supports 29, 32 are rigidly connected by a mechanically strong insulating and hermetic seal 39.

Insulated from and supported on central conductor 29 is a hat shaped grid support member 35 having an annular peripheral flange at its lower extremity with slots and circular centering or lo-

cating V notches formed therein. There is one slot for each grid element 26 which are equal in number to cathode elements 25. Grid elements 26 each hook into grid support member 35 and are accurately positioned by means of the slots and V notches, as will be more fully described hereinbelow, in such manner that each grid element is opposed in close proximity to one of the lands 34 intermediate two adjacent cathode elements. Adjacent their lower ends, each grid element or section 26 is hooked or clipped into a separate flexible support means 36 which in turn are supported from grid terminal ring 37. Support members 28 and 36 are described and claimed in the co-pending application of Willis E. Harbaugh filed May 26, 1949, Serial Number 95,442 (now U. S. Patent No. 2,570,121).

The cathode, grid and beam former arrays form closely positioned, critically spaced units 20 with the cylindric anode. In the tube illustrated the cathode and grid elements are tungsten bars approximately 8 inches in length and extremely ductile at elevated temperatures. It is obvious that such a construction would be subject to objectionable deformation during processing and operation which would render it inoperative were the cathode and grid elements not mounted in such manner that they may freely expand and contract without undergoing deformation. Also, unless the electrodes are mounted by means of knife-edges in accordance with my invention they may be subjected to bending moments resulting in permanent deformation where the electrode supports and associated parts are of higher expansivity than the electrode. Such is the case in tube 24 since support 28 as well as conducting supports 29, 32 are copper while cathode elements 25 are tungsten bars or rods. Magnetic effects on self-heated cathode 25 may also introduce undesirable bending moments if there is any binding between the mounting head and its support.

To insure firm contact of each of the electrodes or electrode elements with its supports by way of the knife-edges, each electrode is maintained in axial tension. Two arrangements for axially tensioning each of the elements independently are utilized in electron discharge device 24. In the case of cathode elements 25 a coil spring 40 in a cylindric tube (shown by solid line in Fig. 1) is provided for each segment of flexible support 28 which acts against an insulating link 41 and which in turn engages rocker arm 42. Rocker arm 42 at one end is free to pivot in a groove in the lower arm of L-shaped ring 43 while its other end is bifurcated and engages in another V groove in the underside of mounting block 44. Coil springs 40 in their cylinders are arranged in circular array in an annular channel formed by conducting support 32 and seal 39. Grid support members 36 are each resilient and include a plurality of steel laminations which serve to maintain each grid element 26 in axial tension without any additional tensioning means.

Cathode and grid elements 25, 26 each have a mounting head 11 with knife-edges 12 and fillet or residual radii 16 formed at each end thereof. As most clearly seen in Figure 1 the upper cathode mounting heads are each individually mounted in separate mounting blocks 44 at the end of each segment of flexible support 28; the lower cathode mounting heads being clipped into slotted annular block 31. The upper grid mounting heads are each clipped into an annular peripheral slotted block on support member 35 while the lower grid

mounting heads are each clipped into mounting blocks 45 on separate resilient supports 36 which are arranged in radial array.

Mounting blocks 44 and 45 are similar to block 14 and are each provided with V grooves and slots. Annular block 31 as well as the annular slotted block on support member 35 each are provided with an annular V groove formed by surfaces 46 and 47 (Figure 6). As apparent in Figure 6, mounting heads 11 with knife-edges 12 are particularly suited for engaging the surfaces of the annular V groove. The knife-edges contact surfaces 46, 47 at points 48, 49, 50 and 51 rather than at the bottom 52 of the V groove. All of the contact points 46, 47, 48 and 49 lie on line C—C which intersects the axis 53 of the electrode element and forms a right angle therewith.

The operation of my improved electrode structure may be best understood from Figure 7 where the expansion and movement of one of the electrode elements of tube 24 is shown diagrammatically. The electrode element as shown is mounted between fixed support 54 and flexible or movable support 55 by means of knife-edges 12 on heads 11 and maintained in axial tension in a manner described hereinabove. As the electrode is heated and expands, movable support 55 changes its position in response to force 56 required to maintain contact by axial tension in the electrode. This new position is indicated by the broken lines. It is seen that all necessary rocking, tilting or displacement motions may take place without introducing bending moments in the electrode.

Knife-edges 12 may be formed by machining or otherwise removing material as well known in the metal working art. However, for a refractory metal such as tungsten, it is necessary to grind away material from each of four directions and at appropriate angles to the axis of the electrode so as to form the two knife-edges. Neck-like constricted portion 57 is also formed at this time. However, I have found that the knife-edges and residual radii or fillets may be best formed by a method which includes hot-heading. First neck-like constricted portions 57 are ground, machined or hot punched adjacent each end of the electrode leaving a relatively short head. This head is then held above a die shaped like block 14 with constricted portion 57 extending down through a closely fitting slot corresponding to slot 15. The surfaces forming the V groove in the die form an angle of 60 degrees corresponding to the intersecting surfaces of the knife-edges to be formed. The head is then heated by flame or other suitable means to a temperature of at least 1000° C. When the head has been heated it is suddenly forced down into the V groove of the die by a hammer-like punch forming knife-edges in the bottom of the V groove. A light tapping readily removes the electrode from the die. The die and punch are preferably mounted in a standard punch press to give a quick but controlled heading stroke. Since the punch and die tend to warm up appreciably due to the heat of the flame and hot work they are best made of a red-hard tool steel. The V groove may be machined in the die before hardening and the slot ground in after hardening.

Electron discharge device electrode structures made in accordance with my invention may be processed as in the case of high temperature bake-outs and operated without undergoing deformation. Such electrode structures have been found to be free of kinks or bowing due to bending moments in the mounting heads even after long periods of operation.

It is apparent that I have provided a highly useful device and method of manufacturing electrode mounting heads which permits accurate close spacings of electrodes free from undesirable deforming forces. Furthermore, by providing pressure contact at predetermined local points in accordance with my invention intermittent contact between the electrode and its supports is effectively eliminated. The foregoing are particularly advantageous in high power or high frequency devices.

While my invention is subject to obvious modifications by those skilled in the art, it is intended to cover all such modifications as come within the scope of the appended claims.

I claim:

1. An electron discharge device, comprising an electrode, support means for said electrode having at least one V groove formed therein, and said electrode having a knife-edge formed thereon and quick detachably seated in said groove.

2. An electron discharge device, comprising at least two co-acting electrodes, support means for each of said electrodes, at least one of said electrodes being elongated and having mounting heads formed adjacent each of its ends, each of said mounting heads having a knife-edge which extends in a plane intersecting the longitudinal axis of said elongated electrode, the support means associated with said elongated electrode including means axially tensioning said elongated electrode and means having spaced V grooves formed therein adapted to receive said knife-edges, and each of said knife-edges being quick detachably seated in one of said V grooves.

3. An electrode structure, comprising an electrode having spaced apart mounting heads formed thereon, each of said mounting heads having a knife-edge formed thereon, means supporting and axially tensioning said electrode and having spaced apart V grooves formed therein, and said electrode being in quick detachable engagement with said means with said knife-edges seated in said V grooves.

4. An electrode structure, comprising an elongated electrode having mounting heads formed at each end thereof, each of said mounting heads having knife-edges extending in a plane which intersects the longitudinal axis of said electrode, means supporting and axially tensioning said electrode, said means having spaced apart slotted V grooves formed therein, said electrode extending through said slots with the knife-edges on one of said heads in one of said V grooves and the knife-edges on the other of said heads in the other of said V grooves.

5. An electrode structure as described in claim 4, wherein said slots are large enough to permit said electrode to move freely therein, said electrode has fillets formed at the points where said knife-edges merge with the longitudinally extending portion of said electrode, and said fillets each engage an edge formed at the intersection of one of said slots and grooves and maintain said electrode centrally positioned in said slots.

6. An electrode, comprising an elongated body portion having integral mounting heads formed adjacent each end thereof, and each of said heads having knife-edges facing each other and extending in a plane which intersects the longitudinal axis of said electrode.

7. An electrode, comprising an elongated body portion having integral mounting heads formed adjacent each end thereof, and each of said heads having knife-edges facing each other and

extending in a line which intersects the longitudinal axis of said electrode at right angles.

8. An electrode assembly, comprising an elongated electrode having a mounting head with a knife edge formed thereon and integral therewith, and support means for said electrode and having a slot formed therein through which said electrode extends with its knife edge in quick detachable engagement with said support means.

9. An electrode assembly, comprising an elongated electrode having a knife edge formed thereon and a portion of reduced cross section merging with said knife edge, and support means for said electrode, said knife edge being in quick detachable engagement with said support means.

10. An electrode assembly, comprising an elongated electrode having portions of reduced cross section adjacent each end thereof and knife edges formed thereon merging with each of said reduced portions, and support means having slots formed thereon through which said reduced portions extend with said knife edges in quick detachable engagement with said support means.

11. An electrode comprising as contiguous parts of an integral structure, an elongated element, a portion of reduced cross-section extending longitudinally from one of the ends of said element, a mounting head of larger cross-section than said portion and attached to the end thereof, two integral parts of the head on opposite sides thereof respectively extending

5 transversely in opposite directions beyond the sides of the reduced portion, each of said two parts having a knife edge on its side toward said elongated element, each of the knife edges merging with said reduced portion, and the two knife edges lying in a common plane.

10 12. An electron discharge device, comprising an electrode, said electrode having a knife edge formed thereon, and conducting lead-in means only quick detachably connected to said knife edge, said electrode being solely connected to said conducting lead-in means.

15 13. An electron discharge device, comprising an elongated electrode having knife edges formed thereon, and conducting lead-in means for said electrode and in quick detachable engagement therewith at said knife edges.
